UNITED STATES PATENT OFFICE.

HARRY H. WALKER, OF GRANTWOOD, NEW JERSEY.

BOOKKEEPING FORM.

Application filed March 20, 1920, Serial No. 367,541. Renewed September 27, 1922. Serial No. 591,002.

To all whom it may concern:

Be it known that I, HARRY H. WALKER, a citizen of the United States, residing at Grantwood, county of Bergen, and State of New Jersey, have invented certain new and useful Improvements in Bookkeeping Forms, fully described and represented in the following specification and the accompanying drawings, forming a part of the same.

This invention relates to improvements in sheets for use in connection with bookkeeping and similar machines, and particularly with such machines of the well known Burroughs type.

In the use, in connection with such machines, of ledger or similar sheets, on which entries such as debits and credits, as well as balances and proofs are made, and which entries it is the object of such machine to make on such sheets, considerable time has heretofore been lost by operators desiring to have good looking work in adjusting such sheet to writing, or entry, position, not only for an initial entry but also for subsequent entries on the sheet.

Objection to the sheets now used has been made because of irregularity in the position of entries thereon, which has been caused by absence of proper guiding means, as the machine referred to is a non-visible, or blind writing machine, and the position at which an entry is made is left to the guess or experience of the operator.

Machines of this class are normally in operating position, that is, with the carriage and carriage roll and attached feed board or sheet supporting shelf so close to writing position in the machine that it is not possible, as the guide on the machine is then hidden from view, for the operator to see the true position of the sheet in the machine in order that he may know where writing will appear. For this reason the carriage and sheet supporting shelf or feed board of the machine must be pushed back, away from the operator, or to non-operative position in order to have them such a distance from the machine proper as to permit the operator to see the guide and the top of the face of the sheet while it is being fed to proper position between the carriage roll and feed roll into the machine. The guides now in use on such machines are hinged to the body of the machine, not to the carriage, (though they move with the carriage when it is

pushed forward or backward) so that when the carriage is in operative or writing position the guide cannot be used to adjust the sheet to proper alignment.

After being placed in feeding position the sheet must be fed or turned around between the carriage roll and its contacting feed roll, with the face of the sheet away from the operator and the sheet upside down either by a pull on the carriage operating handle or by the operator's hand; then, with one of the lateral lines on the sheet, or the printed line thereon if there be any, as a lateral guide, the sheet is adjusted by the operator to align with such sheet guide or rule at the front of the carriage roll as accurately as guess work or the experience of the operator has taught him and the care with which this is done determines the character of the resulting work. The carriage must then be returned to normal or operative position before entries may be made on the sheet. The sheet, together with the carriage roll, must then be turned up a distance, either through pulling the carriage roll operating handle or turning the carriage roll by hand, which distance must be left to the judgment or experience of the operator, in order that an entry can be made in proper position on the sheet. Entries in such machines are generally begun a distance from the top of the sheet, as shown, leaving space for entry of the usual data, comprising the name of the debtor or creditor, his rating, address, terms, etc., which occupies several lines (called the data line). These objections are more pronounced when it is desired to add entries to those already on the sheet than when making initial entries.

The object of the present invention is to save the time now consumed in the hereinbefore mentioned objectionable backward and forward carriage roll manipulation required to attain the necessary proper registry of the sheet in position for entries thereon, and to avoid the necessity that such adjustment be left to the judgment or guess work of the operator, as is now necessary.

With this and other objects in view, the invention consists in certain novel features hereinafter fully described in connection with the accompanying drawings which illustrate the invention in its preferred form, in which drawing—

A represents a ledger sheet of a form in common use, provided with spaces B at the

top for data, such as the name and address of customer, the terms and particular store of the system from which the goods were purchased, etc., and having a pair of double ruled horizontal lines C, D, separating the data spaces from the entry spaces and beneath the upper pair D of which dividing or separating lines entries are made, usually in vertical columns, and usually bearing headings, such as "Charges," "Credits," "Balance," "Proof," and also usually with sub-headings of "Date" and "Description of Goods," etc., as shown. Other and different headings may be substituted or they may be omitted. A series E of numerals, though other suitable identifying marks may be used, beginning, in the example selected for illustration, with figure 1 in the first data space and continuing a chronological order for the number desired or necessary in the series. This series, which may be called the feed series, will preferably be arranged at the left of the "balance" column on the sheet, although it may be otherwise suitably placed on the sheet. The purpose of this feed series of indicating marks or figures E is to notify the operator, as soon as the first indicating mark appears above the carriage guide on the machine (not shown), that the lower or entry part of the sheet is in position for an entry to be made on the part of the sheet F below the lines D.

A second series of indicating or identifying marks J also comprising numerals in the example selected for illustration and also beginning with the figure "1" and located in the first space for entry on the entry part F of the sheet, which series may be termed the entry series, and which series will continue in chronological order to the desired or necessary number to indicate to the operator the line on entry part of the sheet where the entry is to be made, is also preferably employed, and preferably disposed laterally of the sheet from the space it identifies.

When the carriage is in normal or writing position, when a new sheet is in position for writing on the first entry line, figure 1 of the feed series will appear above the guide, but if the carriage be then pushed back to non-writing position, the figure 1 of the entry series will appear above the guide.

These two series of indicating marks will preferably be spaced apart a constantly predetermined distance; that is, the first indicating mark of the feed series E will preferably begin on the first data line B or the first line on the sheet which can be written on in the machine, and each succeeding mark of that series will be one carriage roll or writing space below it, and the figure 1 or first indicating mark of the entry series will preferably be at the point in the entry space 65 F where the first entry is to be made. With

the Burroughs and the ledger sheets I experimented with, I found there were 9 carriage roll spaces between the first data line and the first entry line. Therefore the figure 9 of the feed series in the illustration selected is the first one of the feed series to appear in the entry space of the sheet substantially opposite the "1" of the entry series on that line. I have also found these sheets capable of taking about 44 entries.

It will be understood that other marks than numerals or figures may be used to accomplish the purpose of these two series of marks.

Although it is thought the operation of inserting and aligning a sheet embodying the invention in its preferred form will readily be understood from the foregoing, a description of the operation thereof will now be given.

The sheet A is placed in the machine upside down with its face away from the operator between the carriage roll and feed roll until it is gripped, as is usual in such operations; the sheet is then turned around with the carriage roll and its feed roll either by a pull on the usual operating handle attached to the carriage roll shaft or by the hand of the operator until the first indicating mark, 1, of the feed series on the data line at the top of the sheet appears above the carriage roll guide. The entries (name of customer, etc.) on the data lines are usually inserted on the sheet before it is delivered to the bookkeeping machine operator. When the first indicating mark 1 of the feed series appears within the vision of the operator above the guide on the carriage roll of the machine, it will indicate to him that the sheet is in position for the making of the first entry in any of the columns on the first line in the entry space F of the sheet A.

In selecting a sheet to write upon, and before placing the sheet in the machine, the operator will note whether any entry has been already made in the entry space F thereon and if there has he will also note the indicating mark in the entry series opposite such entry in order that he may know the next number of the entry series and be properly guided as to where to stop and the position on the sheet where the next succeeding entry is to be made in the entry space F.

On the sheets or cards employed in connection with these machines, there are usually one or more blank columns as shown at I and G for indicating whether the entry is a plus or a minus, which spaces may be used for the purpose of affixing thereto, by printing, pasting, or in any other suitable manner applying, either or both the "feed" series of identifying marks, and the "entry" series of identifying marks, or they may both be so applied on or near the vertically ruled lines in such manner as not to in any

way interfere with the entries or ruling, etc., as shown at H.

It will be understood that, although it is preferable to have the two series of marks on the sheet itself, this is not essential, as one of such series of marks may instead be suitably applied to the table or tray where the supply of cards is kept, or such series may be applied to the feed board of the machine, and the operator, when removing the sheet for use, will note whether any former entry has been made. If no previous entry has been made, the operator will so note, but if a previous entry has been made, the operator will carry in his mind the number opposite such previous entry, in order that he may be informed where he is to stop the sheet and make a succeeding entry.

It will be understood that the different series of identifying marks shall be so disposed that the marks of the feed series will indicate to the operator the correct position of writing on the entry part of the sheet substantially opposite the corresponding marks of the "entry" series; that is, the figures of the feed series will constantly predetermine the position for writing substantially opposite the entry series in the entry part F of the sheet, thus, in the case of initial entries, the figure "1" of the feed series shall, as shown, be substantially at the line where the first entry is to be made on the data line, or first line where writing can commence on the sheet and the figure "1" of the entry series shall at the same time be at the point on the sheet where the first entry is to be made in

the entry space under the lines D, which, in the example shown, is substantially opposite figure 9 of the feed series. Similarly, when figure 2 of the feed series appears it will indicate to the operator that the point of entry in the entry space F on the sheet opposite figure 2 of the entry series is in proper position to receive an entry, and so on through the chronological series to the point where the last entry is to be made.

It is not necessary that the indicating marks of the two series be in exact lateral register.

What I claim is:

1. A sheet of the class described having spaces for the reception of typewritten entries, and a series of identifying marks related to said spaces and each identifying a particular space, said series of marks being displaced relative to the corresponding spaces an amount equal to the distance between the printing point of the typewriter and the typewriter scale.

2. A sheet of the class described provided with two vertically arranged series of similar identifying marks, the individual marks of each series being spaced apart the distance of one line, one series of marks being displaced relative to the other series an amount equal to the distance between the printing point and the scale of the typewriter, substantially as described.

In testimony whereof, I have hereunto set my hand.

HARRY H. WALKER.
